UNITED STATES PATENT OFFICE

2,592,225

PORTABLE CATTLE GUARD

Orville R. Winkler, Fort Worth, Tex.

Application April 29, 1946, Serial No. 665,852

2 Claims. (Cl. 256—14)

1

This invention relates to cattle-guards, or the like, which are portable and capable of being collapsed and its principal object resides in the provision of a device adapted for installation in fence lines at entrances to fenced areas in which cattle, or other livestock, are impounded and its design is such as to prevent the passage of livestock through such passage-ways while accommodating vehicular traffic.

An object of the invention is that of providing an inexpensive and simple structure which may be manufactured in uniform designs and structural measurements for economy and that provides a device of the character described suitable for any geographical area and under various conditions.

Broadly, the invention seeks to comprehend the provision of a cattle-guard which is sturdy in construction yet wholly collapsible and capable of being readily packaged or stored and which may be assembled by any person of ordinary skill, and dismantled, if desired, for removal to a different location.

While the foregoing objects are paramount, other and lesser objects will become manifest as the description proceeds, taken in connection with the appended drawings, wherein:

Figure 1 is a perspective view of the invention showing the same completely assembled and illustrating the manner in which the invention is supported, one of the leg members being shown embedded in a concrete footing illustrated in vertical section.

Figure 2 is a fragmentary enlarged perspective illustration of one end of one of the side rails showing the integral tubular socket thereon.

Figure 3 is an enlarged perspective view of one of the vertical standards secured at the ends of the invention in the manner shown in Figure 1.

Figure 4 is an enlarged perspective view of one of the end members of the frame showing the series of spaced tubular sockets thereon, and

Figure 5 is an end elevational view of the invention shown installed over an excavation or ditch, the surrounding earth being illustrated in section, and illustrating one type of concrete footing in which the leg members are embedded.

The invention primarily comprises a pair of end members 10 and 10' which are preferably tubular in section, and which have integral therewith arrangements of tubular sockets 11 extending from one side thereof and in a horizontal direction, as illustrated in detail in Figure 4. The members 10 and 10' are opposingly arranged, as illustrated in Figure 1, so that each arrangement

2

of sockets 11 is directed toward the other and are thus capable of receiving the ends of a plurality of spaced tubular rails 12 forming a grill-like structure between the end members 10 and 10'.

5 Tubular side rails 13 and 13' are arranged on each side of the plurality of spaced rails 12 and on each end thereof are arranged integral sockets 14 and 15 and directed at right angles, as illustrated particularly in Figure 2. The side rails

10 13 and 13' are supported by a plurality of standards 16 whose lower ends are preferably embedded in concrete footings 17, or the like, as shown in Figures 1 and 5. The sockets 15 of the rails 13 provide receptacles for the upper ends of the standards 16 while the ends of the end members 10 and 10' engage the sockets 14 of the member 13 and 13'. In this manner the entire assembly of the tubular rails 12, 13 and 13' is retained in the position illustrated in Figure 1.

20 Each of the side rails 13 and 13' has dual arrangements of sockets 18 and 19 spaced from its ends in the manner shown in Figure 2. This socket arrangement affords a means whereby auxiliary supports can be provided, as shown in Figure 1, the upper ends of spaced standards 20 being received by the vertical sockets 18 while the laterally directed sockets 19 provide receptacles for the ends of transverse tubular members 21 spaced downwardly from the rails so that the members 12 are supported thereby.

30 Each of the end members 10 and 10' has an integral socket 22 intermediate its ends which sockets project upwardly and provide receptacles for the lower ends of vertical standards 23, shown in detail in Figure 3, each having sockets 24 and

35 25 integral therewith and which are arranged in angular positions and paired. The socket arrangements 24 and 25 are smaller in diameter than the sockets 11 and 22 and afford receptacles for the ends of angular braces 26 and 27 shown in Figures 1 and 5.

40 The sockets 28 are arranged at each end of each side rail 13 and are integral therewith, as illustrated in Figure 2, and each is adapted to receive the lower end of each of the angular tubular

45 braces 26 when the invention is assembled as in Figure 1. Other sockets 29 are arranged on each side of the socket 22, as shown in Figure 4, and are opposingly and angularly disposed so as to accommodate the lower end of the angular braces 27 which are the shorter of the vertical end assemblies shown in Figures 1 and 5.

50 Each of the sockets may be provided with a set-screw 30, or other device, by which the members inserted therein can be detachably secured.

In Figure 5 the invention is shown installed over an excavation 31 which may be of any suitable depth and the standards 16 and 20 are provided with ordinary pipe flanges 32 which are supported on concrete footings 33 to afford suitable rigidity for the device. Obviously, the invention may be employed as a bridge over irrigation ditches, drainage ditches, or the like, providing passage for vehicular traffic while preventing livestock from crossing. Temporary passages for livestock may be provided, however, by placing suitable materials on the spaced members 12, 13 and 13'.

Manifestly, the structure herein shown and described is capable of considerable changes and modifications by persons skilled in the art without departing from the spirit and intent of the invention or the scope of the appended claims.

What is claimed is:

1. In a cattle guard adapted for installation over an excavation in a fence line, in combination, a pair of spaced tubular end rails, each having a series of spaced integral tubular sockets along one side, the said rails being opposingly arranged to align the sets of sockets thereon, a plurality of parallel spaced tubes having their ends arranged in said sockets and supported by said end rails, a tubular support for each end of said end rails, a vertical standard detachably supported in each end rail and extending above said rails and said spaced tubes, and a plurality of angular braces detachably arranged on each side of each of said standards.

2. In a collapsible cattle guard for installation in a fence line, in combination, a pair of spaced

tubular end members, each having a series of spaced integral sockets thereon and arranged so that the said sockets on said end members are opposingly aligned, a plurality of spaced parallel tubular members arranged between said end members and detachably supported at the ends in said sockets, a plurality of vertical supports for said end members and said parallel tubular members, a vertical socket formed on each of said end members intermediate its ends, a vertical standard detachably arranged in each of said vertical sockets, a plurality of angular sockets on each end member and spaced from said vertical socket, and angular braces arranged in said sockets and detachably supporting said vertical standards.

ORVILLE R. WINKLER.
